CLAIM

The ornamental design for earphones with charging case, as shown and described.

DESCRIPTION

FIG. 1 is a perspective view of earphones of earphones with charging case, shown separately for ease of illustration;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a perspective view of a charging case of the earphones with charging case, shown separately for ease of illustration and in an open configuration;
FIG. 10 is another perspective view thereof;
FIG. 11 is a front elevational view thereof;
FIG. 12 is a rear elevational view thereof;
FIG. 13 is a left side elevational view thereof;
FIG. 14 is a right side elevational view thereof;
FIG. 15 is a top plan view thereof;
FIG. 16 is a bottom plan view thereof;
FIG. 17 is a perspective view of the earphones with charging case, shown in use with the earphones received in the charging case; and,
FIG. 18 is a perspective view of the charging case of the earphones with charging case, shown separately for ease of illustration and in a closed configuration.
The broken lines in the drawings depict portions of the earphones with charging case that form no part of the claimed design.

1 Claim, 18 Drawing Sheets
